UNITED STATES PATENT OFFICE.

ALBERT A. WELLS, OF DETROIT, MICHIGAN.

INCLOSED NON-ARCING REFILLABLE FUSE.

1,337,806.

Specification of Letters Patent. Patented Apr. 20, 1920.

Application filed May 24, 1919. Serial No. 299,424.

To all whom it may concern:

Be it known that I, ALBERT A. WELLS, a citizen of the United States, and a resident of Detroit, county of Wayne, and 5 State of Michigan, have invented a new and Improved Inclosed Non-Arcing Refillable Fuse, of which the following is a full, clear, and exact description.

This invention relates to fuses, and in 10 particular to a fusible fuse plug of the arc extinguishing type.

An object of the invention is to provide a fuse plug which will extinguish and choke the flame or arc incident to the fusing of 15 the current conducting material. It is also an object of the invention to provide indicating means for showing that the fuse has been blown and no longer conducts current.

Further, it is an object and purpose of 20 my invention to provide a fusible plug with the aforesaid characteristics which will be comparatively simple in structure, inexpensive to manufacture and convenient in application therewith.

25 With the above and other objects in view the invention has relation to a certain combination and arrangement of parts, an example of which is described in the following specification, pointed out in the appended claims, and illustrated in the accompanying drawings, wherein:

Figure 1 shows an elevational view of the fuse.

Fig. 2 shows an end view thereof.

30 Fig. 3 shows an elevation of the fuse with the end caps removed therefrom.

Fig. 4 shows an end view of Fig. 3.

Fig. 5 shows a longitudinal sectional view 40 of the fuse plug, the sectional view being taken upon the line 5—5 of Fig. 2.

Fig. 6 shows a sectional view taken upon the line 6—6 of Fig. 5.

Fig. 7 illustrates a sectional view taken upon the line 7—7 of Fig. 6.

45 Fig. 8 shows a sectional view taken upon the line 8—8 of Fig. 5.

Fig. 9 shows a sectional view of the circuit conducting plug, the view being taken upon the line 6—6 after said fuse element 50 has been fused and the parts have moved into an arc quenching engagement one with the other.

Referring more in particular to the drawings, the numerals 1 and 2 designate a pair 55 of body sections semi-cylindrical in cross section, and placed together to form an ap-

proximately cylindrical fuse member. One of the body sections is provided with a groove which gradually slopes downwardly from the plane toward the circumference 60 of the body. The other body section is provided with an aperture or slot 4 which opens into the slot 3.

The body sections are placed together with the plane faces thereof adjacent one 65 another, and with a fusible ribbon 5 interposed between said sections. The fusible ribbon turns down at each end as shown at 5^a, and lays adjacent the ends of the body sections. A leaf spring 6 is interposed between 70 the sections, and preferably will lie in contact with the section 2 and against one surface of the fusible ribbon. Dowel pins 7 are employed for holding the body sections in fixed position and for maintaining 75 the leaf spring and fusible ribbon in relatively correct position. The free end of the leaf spring has fixed thereto an arc barrier plug 9. This barrier plug is provided with an upper wedge shaped end 80 which conforms in shape and size to the walls forming the aperture 4. The barrier plug is provided with a pin 10. The upper end of the pin is sharpened and adapted to puncture a strip of paper 11 which is 85 pasted or otherwise secured to the body section to cover the aperture 4. The arc barrier plug is provided with a groove or channel upon either side of the pin. The fusible ribbon is provided with an aperture for receiving 90 the wedge shaped extremity 12 of the barrier plug. The fusible ribbon is reduced in size at the barrier plug so that the ribbon will burn out or fuse at that point.

End caps 14 are placed over the assembled 95 body sections which securely hold said sections together. A screw 15 is screw-threaded into one of the body sections and securely engages the metal cap 14 with the turned down end of the fusible ribbon. The caps 100 14 provide the circuit terminals of the fuse plug and are adapted to engage a standard form of fuse block. The fuse plug will be inserted in the fuse block and withdrawn in the usual manner.

When the fusible ribbon becomes overly heated due to an excess flow of current therethrough, the ribbon fuses at the point of greatest resistance, which is adjacent the barrier plug. This causes the tension of the 110 spring 6 to plunge the barrier plug forwardly into the aperture 4. This sudden

action on the part of the barrier plug immediately breaks the arc, and effectually smothers it out since the barrier plug shoulder 12 snugly fits the walls forming the 5 aperture 4. The pin 10 punctures the paper strip 11 and indicates that the fuse has been blown, whereupon it is removed and a new plug inserted.

After the fusible ribbon has blown or 10 melted out and thus opens a circuit in which the fuse is inserted, the plug may be removed and refilled. The refilling is accomplished by removing the screws 15 and end caps 14, after which the two body sections 15 will be separated and a new fusible ribbon 5 inserted therein. Thus this form of fusible plug may readily be renewed.

Having thus described my invention, what 20 I claim as new, and desire to secure by Letters Patent is:

1. A fusible plug, comprising in combination; a pair of body sections, joined together with a fusible ribbon inserted therebetween, a leaf spring carried within one of 25 the body sections, a barrier plug carried by the leaf spring and pressing against the fusible ribbon.

2. A fusible plug, comprising in combination; a pair of body sections, joined together with a fusible ribbon inserted therebetween, a leaf spring carried within one of the body sections, a barrier plug carried by the leaf spring and pressing against the fusible ribbon, and a puncturing pin 35 provided to indicate that the fuse has been blown.

3. A fusible plug, comprising in combination; a pair of body sections placed together, with a fusible ribbon inserted therebetween, a leaf spring, a barrier plug carried on the 40 leaf spring, a strip of paper placed over an opening formed in one of the body sections, and a pin provided to be plunged through the paper when the plug fuses.

4. A fusible plug, comprising in combination; a pair of body sections joined together with an aperture formed in one and a slot formed in the other, a leaf spring with one end thereof fixedly disposed between the body sections and the other end thereof being free to move within the slot, a barrier plug mounted on the free end of the leaf spring adapted to close the opening in one of the body sections, and a fusible ribbon disposed between the body sections holding the barrier plug out of the opening.

5. A fusible plug comprising, a piece of insulating material provided with a deep elongated slot formed therein, a leaf spring with one end fixed to the insulating material, a barrier plug mounted on the free end of the leaf spring, a fusible ribbon applied to the insulating material and having an opening formed therein to permit a portion of the barrier plug to project through said fusible ribbon, another piece of insulating material provided with an opening placed over the fusible ribbon and having an opening to receive the projecting portion of the barrier plug.

ALBERT A. WELLS.
